RICHARD W. KRITZER, OF CHICAGO, ILLINOIS, ASSIGNOR TO PEERLESS ICE MACHINE COMPANY, OF CHICAGO, ILLINOIS

COOLING EVAPORATOR

Application filed August 11, 1930. Serial No. 474,438.

My invention relates to improvements in cooling evaporators, and it consists in the combinations, constructions, and arrangements herein described and claimed.

5 An object of my invention is to provide a cooling evaporator whereby the local air as in a room or a building may be refrigerated.

10 A further object is to provide a device of the type described in which a novel cooling unit is provided and constructed in such a manner that a high degree of cooling efficiency is attained with a minimum amount of structure.

15 A further object is to provide a device of the type described employing novel means through which the humid warm air in a room or a building may be passed through a novel cooling unit and discharged into the room or building, and in which a simple and yet 20 artistic casing is employed for enclosing the mechanism.

25 A further object is to provide a device of the type described in which a novel cooling unit is employed and constructed from a minimum number of parts which are arranged in such a manner as to require a minimum amount of refrigerant liquid and for providing a maximum amount of surface area.

30 Other objects and advantages will appear in the following specification, and the novel features of the invention will be particularly pointed out in the appended claims.

35 My invention is illustrated in the accompanying drawings, forming part of this application, in which

Figure 1 is a side elevation of my invention,

40 Figure 2 is an enlarged detail view, partly in section, of the head,

Figure 3 is a sectional detail view taken along the line 3—3 of Figure 2,

Figure 4 is a sectional detail view taken substantially along the line 4—4 of Figure 3,

45 Figure 5 is a sectional view taken along the line 5—5 of Figure 3,

Figure 6 is a sectional view taken along the line 6—6 of Figure 3,

50 Figure 7 is a top plan view of a portion of the cooling unit, and

Figure 8 is a view of the opposite end of the structure shown in Figure 7.

In carrying out my invention, I make use of a casing comprising a head 1 having an air inlet opening 2 and an air outlet opening 3. 55 The head may be formed integrally with a base portion 4. It will be understood, however, that while I have shown my invention in the present instance in connection with a casing of the pedestal type, other types of 60 casings may be provided. The present casing is one which is adapted to be placed upon a floor or other similar suitable supporting structure. The invention may of course be embodied in any suitable casing, as, for instance, one which may be suspended from a ceiling or supported upon brackets carried by a wall. In the present instance I have shown the head 1 as being formed from suitable sheet material and constructed as a 70 separate part from the base construction 4.

The head may be secured to the flared portion 5 of the base by welding or riveting. The base is also formed from sheet material in the present instance. Such a construction 75 provides a suitable casing for certain conduits which I have shown in Figures 1 and 3 and which will be more fully explained later. The openings 2 and 3 are provided with flanges 6 and 7, respectively. It will be noted 80 in referring to Figure 3 that the flange 6 is considerably longer than the flange 7 and that the flange encloses a fan 8 associated with a motor 9. A second fan 10 associated with a motor 11 is disposed in close proximity to the 85 opening 3. The motors may be mounted upon a supporting member 12, the ends of which are secured to the sides of a cooling unit as by welding, which I have indicated generally at 13, see Figures 2 and 3. The cooling unit 90 comprises spaced-apart sections 14 and 15. The sections are arranged to contain a refrigerant liquid and function as a single unit.

The sections 14 and 15 are identical in construction and are formed from a series of 95 plates. In Figures 4 to 8, inclusive, I have shown the plates in detail. A pair of plates provides an assembly which may be defined as a depending heat exchange member. In referring to Figures 3 and 5, it will be noted 100

that each plate is provided with a plurality of grooves 16 which communicate with cross grooves 17. In referring again to Figure 5, and particularly to Figures 7 and 8, it will be seen that the grooves are formed in such a manner that when the plates are positioned together in a certain way, twice as many refrigerant passageways are provided in each depending heat exchange member as there are grooves in a single plate. The plates may be secured together by welding.

The upper end of each of the plates is formed as at 18, see Figure 7, while the lower ends of the plates are formed as at 19, see Figure 8. Thus it will be seen that an opening 20 is provided in the upper end of each of the heat exchange members and that an opening 21 is provided in the opposite end of each of the members. These openings communicate with the grooves 16 through the medium of the cross grooves 17. A float chamber 22 is disposed upon the upper ends of the sections 14 and 15 and communicates with the interior of the heat exchange members through the medium of the openings 20. The float chamber may be provided with a pair of large openings 23 for communicating with the openings 20 in the sections 14 and 15 of the cooling unit. The upper ends of the heat exchange members may be welded to the float chamber, whereby a rigid construction is attained. The float chamber may be provided with a relatively large opening 24 arranged to be closed by means of a cover 25, see Figure 3. The openings 21 communicate with a cross conduit 26, see Figures 2 and 4. The ends of the heat exchange members are welded to the cross conduit. It will now be seen that a refrigerant liquid entering the float chamber may pass through the heat exchange members by reason of the groove 16 and that the heat exchange members are in communication with one another across the tops and the bottoms through the medium of the float chamber and the cross conduit. It will also be seen that the sections 14 and 15 are in communication with each other through the medium of the float chamber and the cross conduit.

The sections 14 and 15 may rest upon supporting plates 27, see Figure 3. These plates or lugs may be secured to the sides of the flared portion 5. The construction is such, however, that the sections may rest directly upon the flared portion, at which time the plates 27 may be dispensed with. A deflecting plate 28 is disposed between the sections 14 and 15 and secured thereto as by welding.

In referring to Figure 3, it will be noted that the plate 28 is inclined and that the plate 28 serves as a protective element for the motors 9 and 11. Any defrosting in connection with the float chamber which results in a dripping of any liquid from the float chamber will be caught by the plate 28. The

liquid may then run down the sides of the sections 14 and 15. The neck of the base portion, see Figure 3, is provided with a closure plate 29. A drainpipe 30 has one end connected with the plate. A tube 31 passes through an opening 32 in the plate and is arranged for protecting conduits 33 and 34 and wiring 35. The wiring is associated with the motors 9 and 11 for placing the latter in electrical connection with a suitable source of current. That portion of the base 4 above the plate 29 is arranged for receiving any liquid which may defrost from any part of the mechanism contained within the head. The liquid is drained away through the drainpipe 30. Should the drainpipe for any reason become clogged, an accumulation of liquid above the plate 29 will be prevented from damaging the contents of the tube 31 since the latter is liquid proof.

In Figure 3 I have shown the conduit 33 as being connected with the cover 25 and above the liquid inlet 36 which communicates with the conduit 34. The liquid refrigerant enters the float chamber through the conduit 34, while the refrigerant vapor within the float chamber may be drawn therefrom through the conduit 33. A suitable float valve mechanism 37 may be employed for controlling the amount of refrigerant liquid entering the float chamber. Various types of valves may be employed for controlling the liquid level. In Figure 1 I have shown the conduit 33 as being connected with a compressor 38. The conduit 34 is associated with a condenser 39. The latter is connected with the compressor through a suitable pipe 40. The compressor may be operated by means of a motor 41.

From the foregoing description of the various parts of the device, the operation thereof may be readily understood. The fan 8 is preferably of a larger capacity than the fan 10. The fan 8 projects or pushes air through the device, while the fan 10 projects the air from the interior of the head from the latter through the opening 3. The flange 6 is arranged in such a manner that a maximum efficiency is attained. The compressor and its associated mechanism may be located within the basement of a building. The arrangement shown in Figure 1 is merely suggestive and not intended as a limitation in any sense. The refrigerant liquid enters the float chamber from the condenser 39 through the conduit 34. When the sections 14 and 15 have been filled and the liquid has reached a certain level in the float chamber, the float-operated valve will cut off the flow of the liquid to the float chamber.

The fans move air through the sections 14 and 15 of the cooling unit. The heat exchange members provide baffles in the sense that air passing between them is deflected in such a manner that the air sweeps the

entire area of the heat exchange members, which of course increases the transfer of the heat from the air to the heat exchange members. The float chamber and the cross conduit 26 permit the refrigerant liquid to flow through the entire cooling unit. In Figures 2 and 3 I have shown the openings 2 and 3 as being provided with a screen 42 as a protection in connection with the fans 8 and 10. 5 Any suitable structure may be employed for protection against the fans and which provides a minimum obstruction for the movement of air through the head. The wiring for the motors and all of the pipes and their 10 connections are enclosed within the casing so that an ornamental appearance is attained. A suitable switch may be provided for closing the circuit through the motors and positioned in any convenient place not shown. 15 The motors are positioned between the sections 14 and 15 in such a manner that an exceedingly compact construction is attained. 20 It will of course be understood that any suitable means for driving the air through the heat exchange elements may be used instead of the fans 9 and 11. It is equally obvious that the device of my invention is capable of functioning without the use of any fans which are rigidly connected or associated 25 with the heat exchange elements. As a matter of fact, the heat exchange elements disclosed in this application are adapted to cool the air in a room if there are any air currents capable of passing air through the heat exchange members. If desired, the ordinary fan may be used in combination with the heat exchange elements to produce such a current.

I claim:

1. An evaporator element for cooling air including a cooling unit comprising a plurality of substantially parallel spaced-apart heat exchange members, said members being provided with baffles upon each of their sides for deflecting air passing between the same. 40
2. An evaporator element for cooling air including a cooling unit comprising a plurality of substantially parallel spaced-apart heat exchange members, each of said heat exchange members comprising a pair of 45 grooved plates, the grooves in one plate being alternately arranged with respect to the grooves in its companion plate, and means communicating with said grooves for operatively connecting said heat exchange members, whereby a refrigerant fluid may be 50 passed through said members, said means comprising a float chamber provided with a valve for controlling the amount of refrigerant fluid flowing into the cooling unit. 55

60 Signed at Chicago, in the county of Cook and State of Illinois this 6th day of August, A. D. 1930.

RICHARD W. KRITZER.

CERTIFICATE OF CORRECTION.

Patent No. 1,865,924.

July 5, 1932.

RICHARD W. KRITZER.

It is hereby certified that error appears in the above numbered patent requiring correction as follows: In the heading of the drawings, title of invention, for "COOKING EVAPORATOR" read COOLING EVAPORATOR; and that the said Letters Patent should be read with this correction therein that the same may conform to the record of the case in the Patent Office.

Signed and sealed this 25th day of October, A. D. 1932.
